(57) **CLAIM**

We claim the ornamental design for a video camera, as shown and described.

DESCRIPTION

FIG. 1 is a top, front and left side perspective view of a camera of the present invention;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof; and,

FIG. 7 is bottom plan view thereof.

The broken line showing of video camera is included for the purpose of illustrating environment and forms no part of the claimed design. Additionally, the unevenly broken lines in the drawings define the limits of the claimed design.
